UNITED STATES PATENT OFFICE.

GEORGE RACONOVICH, OF SACRAMENTO, CALIFORNIA, ASSIGNOR OF FIFTEEN PER CENT TO O. G. HOPKINS, OF SACRAMENTO, CALIFORNIA.

LOCK.

Application filed June 20, 1921. Serial No. 478,819.

To all whom it may concern:

Be it known that I, GEORGE RACONOVICH, a subject of the King of Serbia, residing at Sacramento, in the county of Sacramento 5 and the State of California, have invented certain new and useful Improvements in Locks, of which the following is a specification.

This invention relates to a lock in which 10 the key-holes are out of alignment thereby preventing any view of the interior of a room through the keyhole, and to a certain extent obstructing the passage of sound waves, and also preventing the ejecting of a 15 key in the lock from the opposite side by the passage of any instrument through the opposite key-hole. The invention also includes a bolt of such construction that when in full locked position it covers one of the key- 20 holes, in practice the exterior one, thus preventing introduction of any key or type of lock picking device into the lock; the bolt extending so far into the keeper when in full locking position as to make it practi- 25 cally impossible to "jimmy" the lock by forcing or prying the bolt back by means of an instrument inserted at the edge of the door.

With these various objects in view the in- 30 vention consists of the following novel fea- tures of construction hereinafter described, pointed out in the claim and shown in the drawing, in which:—

Figure 1 is a side elevation of the lock, the 35 outer face plate being removed and the ex- terior key-hole being indicated in dotted lines.

Figure 2 is a partial end elevation and 40 partially in section on the line 2—2 of Fig. 1.

Figure 3 is a section on the line 3—3 of Fig. 1.

Figure 4 is a detail perspective view of the locking bolt.

Figure 5 is a sectional detail view showing the position occupied by the key when inserted.

In the drawings 1 designates the lock case and 2 the usual bolt actuated by a knob 50 shaft 3. A bar 4 extends horizontally from end to end of the lock and carries pins 5 and 6. A tumbler 7 is provided on its upper edge with lugs 8 and 9. The tumbler is pivoted by hanging the lug 8 on the pin 5 55 of the bar 4. The lug 9 forms a bearing for

a pin 10. A spring 11 has one end portion secured to the bolt 2, is coiled around the pin 5, passed through the pin 10 and rests under the pin 6. This spring throws forward the bolt 2 and also holds the tumbler 60 7 in normal position.

The key-operated bolt 12 is slotted longitudinally as shown at 13 and the tumbler 7 works in this slot.

One side of this bolt has three notches 14 65 cut in its upper edge, and these notches co-operate with a lug 10^a carried on one side of the tumbler, adjacent the lug 9 and immediately to the rear of the pin 10 so that the spring 11 will hold the lug firmly in one of the notches, preventing longitudinal movement of the bolt until the lug is disengaged.

On the under side the bolt has three notches 15 adapted to be engaged by the 75 key 19.

The casing is provided with offset key-holes 16 and 17, the one at 17 being that 80 preferably operated from the outer side of the door, though of course the lock can be placed in any position desired. The cover plate of the casing opposite each key-hole is countersunk as at 18 to receive the end of the key. This limits the extent to which the key can be inserted and also acts as a 85 guide ensuring proper insertion of the key before turning.

When the key is inserted in keyhole 16 it is turned twice. Before the key engages the first notch 15 it lifts the tumbler clearing the lug 10^a from its notch 14. The second turn of the key again lifts the tumbler and the key then engages the second notch 15, throwing the bolt 12 the entire distance 90 of its travel and bringing a portion of it over the key hole 17.

Therefore when the door is locked from the inside it is impossible to insert any key into the lock through the outer key-hole 17, or to gain access to the lock casing to pick it. When the key is inserted 100 into the key-hole 17 only one turn of the key is made, and the key-hole remains uncovered.

Any form or style of key may be used 105 which will operate the lock.

What I claim is:—

In a lock, a casing having oppositely placed key-holes, a slid able bolt, said bolt having a series of three equally spaced notches on its under side and adapted to 110

be engaged by a key inserted through either keyhole, the keyhole in one side of the casting being offset with respect to that on the opposite side, said notched portion of the 5 tumbler being so arranged with respect to said keyholes that when inserted through one keyhole it is adapted to engage two of said notches in succession, and when inserted through the other to engage only 10 one of said notches, thereby throwing the bolt a greater distance when locked from one side of the door than when locked from the opposite side, the said bolt having a guard portion adapted to cover an exterior keyhole when the bolt is moved 15 to its extreme locking position, the bolt having also notches on its upper face, three 20 in number, a tumbler having a lug adapted to engage one of said notches in each of the three positions of the bolt, a pin carried by the tumbler, a pin fixed above the tumbler, and a spring secured at one end 25 and passing through the tumbler pin and having its free end resting under the fixed pin.

In testimony whereof I affix my signature.

GEORGE RACONOVICH.
